(57) **CLAIM**

The ornamental design for a deck-mount faucet, as shown and described.

DESCRIPTION

FIG. 1 is a perspective view from in front, above, and to the right of the faucet according to the invention;

FIG. 2 is a front elevational view of the faucet;

FIG. 3 is a rear elevational view of the faucet;

FIG. 4 is a right-side elevational view of the faucet;

FIG. 5 is a left-side elevational view of the faucet;

FIG. 6 is a top view of the faucet; and,

FIG. 7 is a bottom view of the faucet.

The broken line showing in FIG. 7 is included for the purpose of illustrating and forms no part of the claimed design.
